UNITED STATES PATENT OFFICE.

DANIEL M. STUMP, OF CHICAGO, ILLINOIS, ASSIGNOR TO THE ALBERT DICKINSON COMPANY, OF CHICAGO, ILLINOIS, A CORPORATION OF ILLINOIS.

CLOSURE FOR CULTURE CONTAINERS.

Application filed July 6, 1926. Serial No. 120,612.

This invention relates to a stopper or closure for culture containers. One of the objects of the present invention is to provide a stopper or closure for culture containers which is simple in construction and efficient in operation.

A further object of the invention is to provide an improved closure or stopper for a culture container having an aperture therein through which the needle for inoculating the medium in the container may be inserted and the aperture effectively closed by pressing the closure or plug into the mouth of the container.

These and other objects are accomplished by providing a construction and arrangement of the various parts in the manner hereinafter described and particularly pointed out in the appended claims.

Referring to the drawings,

Fig. 1 is a fragmentary cross-sectional view of a portion of a culture container showing one form of my improved closure or stopper construction mounted therein.

Fig. 2 is a fragmentary cross-sectional view showing the form of the stopper shown in Fig. 1 depressed into the mouth of the container.

Fig. 3 is a fragmentary cross-sectional view of a portion of a culture container showing another form of closure member.

Fig. 4 is a cross-sectional view of the closure member shown in Fig. 3 depressed into the mouth of the container.

Fig. 5 is a fragmentary cross-sectional view of the culture container showing another form of a closure or stopper for containers.

Fig. 6 is a fragmentary cross-sectional view of the stopper shown in Fig. 5 depressed into the mouth of the container.

Fig. 7 is a fragmentary cross-sectional view of a culture container showing another form of a closure member mounted in the mouth of the container, and,

Fig. 8 is a fragmentary cross-sectional view of the closure or stopper shown in Fig. 7 depressed into the mouth of the container.

In inoculating a media in a container in which a culture such as bacteria or other organism may grow, I have found it highly desirable to provide as small an aperture as is possible through which the needle for

inoculating the media is inserted in order that the media is not exposed to the air during the operation of inoculation. This is to prevent the possibility of foreign organisms from entering the container.

In the drawings I have illustrated several forms which my invention may assume in practice, one form of which is shown in Figs. 1 and 2 and comprises a stopper or closure member as shown at 10 which is preferably in the form of an inverted frustum of a cone which is adapted to be mounted in the mouth 11 of the culture container. This stopper or closure member like the other stoppers shown in the other forms in the drawings is preferably made from the wood of *Ochroma lagopus*, (balsa wood) or other material of a spongy fibrous nature in which the fibers of the stopper run longitudinally of the axis of the stopper. Stoppers made from ordinary cork are not suitable for present purposes for the reason that when subjected to steam under pressure, the cork loses its characteristic properties and becomes soft and impractical as a stopper. Close fibred woods which will withstand the sterilizing steam, while sufficiently porous to permit the passage of any air through them, (a slight amount of air being necessary to keep the cultures alive) become so tightly seated in the bottle necks that it is impossible to remove them and it is often necessary to break the bottle in order to obtain access to the contained cultures.

As a result of long experimentation I have found that balsa wood is very satisfactory for culture container stoppers. This wood has the property of resisting and not being materially affected by steam under pressure employed in the sterilizing process so that the culture containers can be closed before the steaming operation is performed. Balsa wood stoppers are sufficiently porous so that the requisite amount of air necessary to maintain life in the culture over a considerable period of time, will pass through the balsa wood stoppers and in addition balsa wood stoppers can be withdrawn from the containers without breaking the glass. In the form shown in Fig. 1, I have shown an orifice or aperture 12 extending longitudinally of the stopper in a line substantially parallel with one side of the closure mem-

ber. When the plug or closure member is lightly placed in the mouth of the container, as shown in Fig. 1 of the drawings, the needle carrying the bacteria or other organism to inoculate the medium within the container is inserted through the aperture 12 and after the culture has been deposited in the container, the needle is withdrawn and the stopper or closure member is pressed 10 into the mouth of the container to the position shown in Fig. 2 thereby closing the aperture 12 by the wedging action of the tapered sides of the plug on the mouth of the container.

16 The form shown in Fig. 3, the aperture or orifice 13 for the needle assumes a diagonal position in the plug in which it extends from the side of the plug at a point substantially midway of its ends, to a point 20 which is substantially the center of the smaller end of the plug, so that when the stopper is depressed into the mouth of the culture container or to the position shown in Fig. 4, the aperture will be sealed because 25 the open end of the aperture is forced below the top surface of the mouth of the container.

In the modified form shown in Fig. 5, the aperture 14 for receiving the inoculating 30 needle is formed on the tapered side of the stopper or closure and when the stopper is forced into the mouth of the culture container or to the position shown in Fig. 6, the aperture is effectually closed by the 35 compression of the material during the operation of forcing the plug or closure into the mouth of the container as clearly shown in Fig. 6.

In the modification shown in Figs. 7 and 40 8, the plug or closure is provided with an inoculating needle receiving aperture 15 which extends from a point substantially midway of the ends of the closure to the smaller end thereof and on one of the 45 tapered sides of the closure member as clearly shown in Fig. 7 so that when the needle is withdrawn after inoculating the media in the container the plug may be depressed, forcing the upper portion of the closure to a position so that the opening used for inoculating is effectually closed by the opening 50 being forced below the top surface of the mouth of the container as clearly shown in Fig. 8.

55 In the operation and use of my improved closures or stoppers, the containers are filled with suitable media in which culture such as bacteria or other organism may grow. The plugs, as above described, are lightly 60 placed in the mouth of the containers and after being sterilized and cooled, a needle or other carrier of organism is inserted through the aperture in the plug and discharged into the medium within the container. After this has been done the needle

is withdrawn and the closure is forced into the mouth of the container effectively closing the opening.

The subsequent growth of any organism through the pores of the plug may be prevented by treating the plug with chemicals unfavorable to the growth of such organism or by covering the mouth of the container with a substance containing chemicals unfavorable to such foreign growth.

70 While in the above specification, I have described several forms which my invention may assume in practice, it will, of course, be understood that various other modifications 75 may be made without departing from the spirit and scope of my invention as expressed in the following claims.

What I claim as my invention and desire to secure by Letters Patent is:

I claim:

1. A closure for culture containers formed of material sufficiently porous to permit the passage of sufficient air therethrough to maintain life in the culture for a considerable period of time and in transit, said closure being sufficiently elastic to permit the withdrawal thereof from the container and also possessing the characteristics of retaining its elasticity and required porosity when subjected to the action of sterilizing steam 95 and pressure.

2. A closure member for culture containers, comprising a tapered plug made of a porous-spongy material in which the fibers extend longitudinally of the plug, said plug being sufficiently porous to permit the passage of the required amount of air therethrough to maintain life in the culture within the bottle and being sufficiently elastic to permit ready withdrawal of the closure from the container and also possessing the quality of retaining its elasticity when subjected to the action of sterilizing steam and pressure, said plug having an aperture therein wherein said plug may be depressed in the mouth of said container to a position in which the opening of said aperture may be forced below the top of the mouth of the container.

3. A closure for culture containers made of *Ochroma lagopus* with the fibers extending longitudinally thereof, said closure being sufficiently porous to permit the ingress of air therethrough into the container for the cultures and sufficiently elastic under all conditions to permit the withdrawal thereof from the container and possessing the quality of retaining its required porosity and elasticity when subjected to the action of sterilizing steam and pressure.

4. A closure member for culture containers having an aperture through a portion thereof for receiving an inoculating needle, said aperture being so located in said plug that when the plug is depressed 130

into the mouth of said container, said aperture will be effectually closed, said closure member being of sufficient porosity to permit the required ingress of air to keep the cultures within the container alive and further characterized by its capability of maintaining its elasticity to permit ready with-

drawal thereof from the bottle after being subjected to the sterilizing action of steam and pressure.

In witness of the foregoing I affix my signature.

DANIEL M. STUMP.
